(57) **CLAIM**

The ornamental design for a bottle, as shown and described.

DESCRIPTION

FIG. 1 is top, front, right perspective view showing my new design;

FIG. 2 is a bottom, front, right perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof;

FIG. 8 is a bottom plan view thereof;

FIG. 9 is a cross-section view thereof taken along line 9-9 of FIG. 6; and,

FIG. 10 is a cross-section view thereof taken along line 10-10 of FIG. 6.

The dash-dash broken lines depict portions of the bottle. The dash-dot-dash broken lines depict boundaries of the claim. The broken lines form no part of the claimed design.
